CLAIM

I claim the ornamental design of a game board, substantially as shown and described.

DESCRIPTION

FIG. 1 is a top plan view of a game board embodying my invention;

FIG. 2 is a bottom plan view of the game board;

FIG. 3 is a front elevation of the game board, the rear elevation being identical; and,

FIG. 4 is a left side elevation of the game board, the right side elevation being identical.

The contrasting surface shading in FIG. 1 represents contrasting surface treatment of the respective components.
